UNITED STATES PATENT OFFICE.

ALFRED L. WILKES, OF SANTA ANA, CALIFORNIA.

DESIGN FOR A BEET-PICK POINT.

47,240.

Specification for Design.

Patented Apr. 13, 1915.

Application filed July 28, 1914. Serial No. 853,718. Term of patent 14 years.

To all whom it may concern:

Be it known that I, ALFRED L. WILKES, a citizen of the United States of America, residing at Santa Ana, in the county of Orange, State of California, have invented a new, original, and ornamental Design for a Beet-Pick Point, of which the following is a specification, reference being had to the accompanying drawings, forming part hereof, and in which—

Figure 1 is a front elevation of a beet pick point illustrating my new design; Fig. 2 is

a side elevational view of the same; Fig. 3 is a rear elevational view of the same; and Fig. 4 is a cross-sectional view taken on the line 4—4 of Fig. 2.

I claim:

The ornamental design for a beet pick point, as shown.

ALFRED L. WILKES.
